MANUFACTURE OF MINIATURE
THERMIONIC DEVICES

Joseph J. Bannon, Jr., North Arlington, N. J., assignor to Tung-Sol Lamp Works, Inc., Newark, N. J., a corporation of Delaware

Application July 1, 1943, Serial No. 493,027

7 Claims. (Cl. 219—10)

1

This invention relates to the manufacture of thermionic devices.

In the manufacture of thermionic devices or mounts, and particularly mounts for miniature radio tubes of the type in which a sealing-in button is spaced from the grid-plate structure, difficulties are experienced in obtaining accurate alinement of the buttons with the grid structures when the connecting wires between the two elements are welded together.

The invention resides in a novel and improved method and apparatus for assuring the exact alinement and spacing of the elements of the mount and facilitating the welding of the connecting wires.

Further objects of the invention will herein-after appear.

For a better understanding of the invention, reference may be had to the accompanying drawings wherein—

Figs. 1 and 2 are perspective views illustrating two of the steps of applicant's invention;

Fig. 3 is a side view of a mount for a miniature tube which is assembled according to applicant's invention;

Fig. 4 is an elevational view of a means for facilitating the practice of the method;

Fig. 5 is a plan view thereof; and

Fig. 6 is a view similar to Fig. 4, disposed at right angles thereto.

The miniature mount which I have chosen for illustration of the invention comprises concentric, cylindrical plates, one of which is indicated by the numeral 1, with mica or other insulating discs 3 and 4 fastened at the top and bottom of these plates respectively and holding them in concentric relation. The discs 3 and 4 may be slightly spaced from the ends of the plates, as illustrated. The particular structure of this mount does not enter into the present invention and accordingly its details are not illustrated. It comprises a multiplicity of wires 5, 6, 7, etc., projecting out through the disc 3 from the elements of the mount and forming terminals for these elements. A sealing-in button or disc 10 of glass or the like carries a multiplicity of terminals 11, 12, 13, etc., for forming an electrical connection outside of the envelope or tube (not illustrated). These terminals project through the button or bead 10 and have corresponding connections 11', 12', 13', etc., on the opposite or inner side of the button for forming electrical connections with the wires 5, 6, 7, etc., and for carrying the plate element 1, 3, 4.

These two elements, namely the button 10 and

2

the plate element 1, are illustrated in Fig. 1 before the fastening or welding of the connections 11', 12', 13', etc., to the electrical terminals 5, 6, 7, etc. is effected. The difficulty in the conventional practice of fastening and welding these connections is that the percentage of rejects is unduly large because of improper spacing and misalinement of the button 10 on the one hand and part 1, 3, 4 on the other hand. These objections of the conventional practice are obviated by my invention, which resides in the method and apparatus hereinafter set forth.

In order to obtain exact and precision spacing and alinement of the button 10 with respect to the cylindrical part 1, 3, 4, these parts are separately mounted on a spacing and alining device comprising a V-shaped alining and spacing element A for holding and alining the cylindrical part 1, and an alining and spacing element B for accommodating and holding the button 10. The cylindrical part 1 is properly alined and positioned on the element A in any suitable manner as, for example, by holding the part 1 firmly within the V of the holder with some convenient part of the part 1 as, for example, the disc 3 or 4 bearing a predetermined relation with respect to the V support. If desired, the spacing may be such that the projecting edge of the disc 4 bears against the lefthand edge of the V holder (Figs. 1, 2 and 4). The element B comprises an arcuate or semi-annular groove open at the top for the reception of the button 10 and may be formed conveniently of an annular angle iron 35 formed into an arc and a corresponding arc-shaped plate 34 fastened thereto in any suitable manner as, for example, by the bolts 17. The angle iron 35 in the particular embodiment shown is provided with an internal member or shoulder 18 which assists in the holding and precision alining of the button 10. If desired, a shim 19 may be provided between the plates 35 and 34, namely, in line with the bolts 17, which pass through openings formed in the shim for the purpose of adjusting or spacing the plate 34 with respect to the plate 35 the desired amount to accommodate the button or disc 10.

The precision alining and spacing elements A and B are supported, in the particular embodiment shown, by a standard 20 whose lower end is pivotally mounted at 21 on a base element 22; the base element 22 comprising a pair of spaced upstanding members 22' for receiving the flattened lower end of the standard 20. By this arrangement the standard 20 may be swung back and forth about the pivot 21 in a plane at right

angles to a central plane through the elements A and B. The lower corners 23 of the flattened end 20' of the standard may serve as the means for limiting the swinging movement standard 20 through a predetermined arc on either side by engaging the surface 24 or bottom of the groove formed by the upstanding supports 22'. The element A is mounted on a standard 25 which in turn is mounted for swiveling and adjusting movements in a bracket 26 projecting at right angles to the standard 20. The bracket 26 is carried by a collar 26' surrounding the standard 20 and being adjustable longitudinally of the standard 20 by releasing and fastening, after adjustment, a set-screw 27. If desired, the standard 25 may be adjusted away from and toward the standard 20, and thus the element A is universally adjustable with respect to the element B.

The elements A and B are mounted adjacent an electric welding machine comprising a stationary electrode 30 and a movable electrode 31. The other elements of the welding machine are omitted for convenience in illustration since the structure of the machine may be of any conventional character. The method of assembling and forming a unitary structure of the parts 1 and 10 with precision alignment and spacing is as follows: With the elements A and B adjusted with respect to each other to accommodate and properly align and space the parts 1 and 10, the latter may be and preferably are positioned respectively on the elements A and B by hand manipulation. Fig. 1 illustrates the operator in the act of positioning these parts 1 and 10 respectively upon the elements A and B. With these parts thus assembled on the elements A and B and there firmly held by the fingers, as illustrated in Fig. 2, the precision device is swung over about the pivot 21 to a position to bring two of the connections to be fastened or welded to a position resting upon the stationary electrode 30. Thus one of the connecting wires 11', 12', 13', etc., is to be welded to one of the connecting wires 5, 6, 7, etc., extending from the plate, grid, heater and cathode elements of the mount. In the particular embodiment illustrated in Fig. 2, the connection 11' leading from the terminal 11 is to be welded to the terminal 5. The welding of these connections together is effected by bringing the movable electrode 31 of the electric welding machine into engagement with the two wires 5 and 11' which are resting upon the electrode 30 in contact with each other ready for the welding step. After the welding of one of the connections is effected, the operator, while still holding the parts 1 and 10 firmly in the elements A and B and in the aligned and spaced position, proceeds to join and weld another one of the connections, preferably one which is spaced a considerable distance from the weld between 5 and 11' as, for example, the weld between another grid plate connection and connection 15'. With these two welds formed respectively between 5 and 11' on the one hand and at 15' on the other, it is no longer necessary to hold the parts 1 and 10 in the elements A and B, since they are now aligned and spaced exactly as desired, and the connections 11' and 15' are of sufficient strength to hold the parts 1 and 10 in alignment while the remainder of the welds are formed. In other words, the operator, if she desires, may now release the elements A and B, move the standard 20 about the pivot 21 away from the position underneath the stationary electrode 30 and then proceed to effect the other welds between the

various connections without danger of producing a misalignment between the elements 1 and 10. Such hand operations without the use of the elements A and B may be effected very rapidly and economically with maximum production, while effecting at least two of the welds or connections which are in substantial spaced relation to each other with the parts 1 and 10 precision aligned and spaced on the elements A and B, a firm and sufficiently rigid fastening of the part 1 to the part 10 is effected for permanently retaining the alignment and spacing during the further welding and manufacturing steps.

I claim:

1. A means for facilitating the precision alignment and spacing of the sealing-in part and the grid-plate part of a miniature radio tube comprising a standard pivotally mounted for swinging movements toward and away from an electric welder and aligned holding devices carried by said standard for supporting in precision alignment and spacing relation said parts while effecting the welding of terminal connections between the parts the aligned holders comprising a V-shaped member for holding the grid-plate part and a narrow arcuate holder having an arcuate groove for the reception of a button sealing-in part at right angles to the axis of the V member.
2. A means for facilitating the precision alignment and spacing of the sealing-in part and the grid-plate part of a miniature radio tube comprising a standard pivotally mounted for swinging movements toward and away from an electric welder and aligned holding devices carried by said standard for supporting in precision alignment and spacing relation said parts while effecting the welding of terminal connections between the parts the aligned holders comprising a V-shaped member for holding the grid-plate part and a narrow arcuate holder having an arcuate groove for the reception of a button sealing-in part at right angles to the axis of the V member.
3. A means for facilitating the precision alignment and spacing of the sealing-in part and the grid-plate part of a miniature radio tube comprising a standard pivotally mounted for free swinging movements toward and away from an electric welder and aligned holding devices carried by said standard for supporting in precision alignment and spacing relation said parts while effecting the welding of terminal connections between the parts, said aligned holding devices comprising an open sided trough-shaped member for holding the grid plate part and a holder having a narrow recess for the reception of a button sealing-in part at right angles to the axis of the trough-shaped member.
4. A means for facilitating the precision alignment and spacing of the sealing-in part and the grid-plate part of a miniature radio tube comprising a standard and aligned holding devices carried by said standard for supporting in precision alignment and spacing relation said parts while effecting the welding of terminal connections between the parts, the aligned holders comprising a V-shaped member for holding the grid-plate part and a narrow arcuate holder having an arcuate groove for the reception of a button sealing-in part at right angles to the axis of the V member.
5. A means for facilitating the precision alignment and spacing of the sealing-in part and the grid plate part of a miniature radio tube comprising a standard pivotally mounted for free swing-

ing movements toward and away from an electric welder and aligned holding devices carried by said standard for supporting in precision alignment and spaced relation said parts while effecting the welding of terminal connections between the parts, said aligned holding devices comprising an open sided trough-shaped member for holding the grid plate part and a holder rigidly mounted with respect to the trough-shaped member and extending laterally with respect to the axis of the trough-shaped member for holding the button sealing-in part at right angles to and in axial alignment with the trough-shaped member and in a predetermined radial position with respect to the grid plate part.

6. In the manufacture of a miniature radio tube, the method of assembling and joining together in precision alignment and spaced relation a cylindrical grid plate part having a multiplicity of spaced terminal connections and a button sealing-in part having a multiplicity of corresponding and circumferentially spaced terminal connections to be fastened to the other terminals, which comprises the steps of supporting and firmly holding the parts in precision aligned and spaced relation and in a position wherein the terminals of the parts may be electric welded together and while thus holding the parts in precision aligned and spaced relation, fastening together at least two pairs of the terminals which are spaced from each other a greater distance than other pairs of connections and then with the parts thus rigidly mounted as a unit with the parts in axial and radial alignment and at least two of the connections already formed electric welding the other corresponding connections without the use of holding and aligning devices.

7. The method of assembling and electrically connecting the grid plate part and the button sealing-in part of miniature radio tubes, said grid plate part having a multiplicity of spaced relatively rigid terminal wires electrically connected with its elements and extending from one end thereof and the button sealing-in part having a multiplicity of corresponding terminal wires ex-

tending therethrough, the ends of said wires on one side thereof being spaced and arranged to correspond with the spacing and arrangement of the terminal wires extending from the grid plate part, said method comprising the steps of resting and supporting the parts on spaced and aligned supporting and aligning means, firmly pressing the parts against said means with the parts in precision alignment and spaced relation one with the other for attachment of the corresponding terminal wires of the parts, and while so firmly pressing the parts against said means electric welding together at least two pairs of terminal wires which are spaced from each other a distance greater than other pairs thereby fixedly mounting in precision alignment and spaced relation the grid plate part to the button sealing-in part and completing the electric circuit between the pairs of wires so welded and then with the parts thus rigidly mounted one with respect to the other electric welding the remaining corresponding pairs of terminal wires without the aid of the supporting and aligning means.
